(74) Attorney, Agent, or Firm — Alan D. Kamrath;
Kamrath IP Lawfirm, P.A.(57) **CLAIM**

The ornamental design for a prying tool, as shown and described.

DESCRIPTION

FIG. 1 is a perspective view of a prying tool showing my new design;

FIG. 2 is a front view thereof;

FIG. 3 is a rear view thereof;

FIG. 4 is a left view thereof;

FIG. 5 is a right view thereof; and,

FIG. 6 is a top view thereof.

The broken lines in FIGS. 1 and 3-6 indicate boundary and do not, themselves, form part of the claim.
